UNITED STATES PATENT OFFICE.

LIONEL M. WOOLSON, OF DETROIT, MICHIGAN, ASSIGNOR TO PACKARD MOTOR CAR COMPANY, OF DETROIT, MICHIGAN, A CORPORATION OF MICHIGAN.

INTERNAL-COMBUSTION ENGINE.

Application filed November 19, 1923. Serial No. 675,503.

This invention relates to internal combustion engines and particularly to starting mechanism therefor.

Heretofore it has been proposed to start 5 automobile engines by injecting acetylene gas into the cylinders and igniting the charge of gas therein. This method of starting required either a distributor timed with the engine for distributing the gas to the 10 various cylinders, or a multiple pump or pump connections for injecting gas into all of the cylinders. It had the disadvantage of complication and of making it impracticable to run the engine for any length of 15 time on the acetylene gas itself.

In the recent development of internal combustion engines for aviation use, and particularly large bore engines for dirigible use, starting difficulties have been encountered as they were in the early days of the 20 automobile industry. The ordinary electric starter of the automobile engine is nowhere near large enough to turn over these big aviation engines and if they are increased 25 in size and provided with batteries sufficient to turn over these large engines their weight is such as to make them prohibitive for aviation use. For instance, for cranking a six-cylinder aviation engine of 65 $\frac{1}{2}$ inch 30 bore and 7 $\frac{1}{2}$ inch stroke, the starting motor would weigh fifty pounds or more and the battery around seventy-five pounds. When it is considered that six or more of these 35 engines are used on a dirigible it will be seen that to equip the engines with starting mechanism of that type would be equivalent to carrying another half dozen passengers as dead weight.

In warmer weather and with high grade 40 gasoline these large aviation motors may be started by hand cranking and numerous forms of reduction gearing have been provided for hand cranking. In the cold weather, however, hand cranking on gasoline 45 is entirely unsuccessful and the old means of charging the cylinders with acetylene gas have been resorted to. These have been found more or less impracticable due to complication and to inability to run long 50 enough on the acetylene gas to insure starting on gasoline. Difficulties have been encountered also due to the fall in pressure as the acetylene gas is withdrawn from its storage tank.

55 One of the objects of the present inven-

tion is to provide a novel and efficient means for feeding acetylene or a similar gas to an internal combustion engine at a low pressure.

Another object of the invention is to provide a measuring device for charging an internal combustion engine with explosive gas.

Another object of the invention is to provide an internal combustion engine with a practical means for feeding to it under a 65 low pressure a charge of explosive gas drawn from a tank under high pressure.

Other objects of the invention will appear from the following description taken in connection with the drawings, which form a 70 part of this specification, and in which:

Fig. 1 is a plan view, somewhat diagrammatic, of an internal combustion engine and gas feeding means embodying the invention;

Fig. 2 is a vertical section through the 75 measuring device;

Fig. 3 is a section substantially on the line 3—3 of Fig. 2; and

Fig. 4 is a section substantially on the line 4—4 of Fig. 2.

Referring to the drawings, 10 represents an internal combustion engine having intake conduits 11 which are fed with mixture from a conduit 12 to which the engine carburetor 13 is connected. The engine is provided with sparking mechanism comprising a distributor 14, wiring 15, and spark plugs 16, one for each of the six cylinders of the engine shown. The engine is of the usual internal combustion engine type having inlet 80 and exhaust valves operated by a cam or other shaft driven by two-to-one gearing shown at the front end of the engine at 17. Instead of feeding an explosive charge of gas to the engine cylinders, the present invention 85 contemplates feeding explosive gas at low pressure into the intake conduits 11 where it will be drawn into the cylinders through the engine intake ports. The source of gas supply is indicated at 18 being in the 90 form of a tank adapted to hold acetylene or other gas at a pressure of two thousand pounds or more. This tank is connected to the intake conduit 11 by pipes 19 and 20 and by small inlet connections 21.

105 Between the pipes 19 and 20 is a measuring device 22 shown in elevation in Fig. 1 and in section in Fig. 2. Referring to this device it will be seen that it is a tubular receptacle having an inlet port or passage 110

23 and an outlet port or passage 24, both of which are controlled by a single hand operated valve 25. A pressure gauge 26 is connected to the outlet passage 24 so that the pressure within the receptacle may always be observed.

The valve 25 has a central bore 27 plugged at 28 and connecting with this bore 27 are right angle passages 29 and 30 arranged in 10 different zones of the valve. These passages 29 and 30 are arranged to connect at different times with the passages 23 and 24 respectively and they also respectively connect with passages 31 and 32 formed at the base 15 of the receptacle adjacent the valve 25. The passages 31 and 32 connect with pipes 19 and 20 respectively.

The valve 25 is provided with a handle 33 for turning it and a pointer 34 for indicating its position. The valve is in normal or "off" position in the various figures of the drawing. The handle may be moved to the left, in Fig. 1, to one of the dotted line positions shown and the receptacle 22 25 will then be connected directly with the tank 18 through the pipe 19, this being the "charge" position of the valve, or it may be turned to the right, in Fig. 1, to the other dotted line position, and the receptacle 30 22 will then be connected with the intake conduit 11 of the engine, through the pipe 20.

The inlet passage 23 of the receptacle 22 is also automatically controlled, a diaphragm 35 operated valve being provided for the purpose. This valve is indicated at 35 and a diaphragm 36 is shown in the upper part 35 of the receptacle 22 and connected to the upper end of the stem of the valve 35. A 40 spring 37 presses the diaphragm yieldingly downward and a bolt 38 adjusts the tension of the spring 37. A lock-nut 39 secures the bolt 38 in adjusted position.

Thus it will be seen that as the pressure 45 in the receptacle rises to a point where the tension of the spring 37 is overcome, the diaphragm 36 draws the valve 35 upwardly and closes it on its seat. This is preferably at about five pounds pressure so that if the 50 pressure gauge 26 indicates a pressure higher than five pounds it will be known that the valve 35 is leaking or that the device is otherwise out of order. The construction, however, is so simple that there is little likelihood of anything going wrong with it.

In the operation of the device, the tank 18 being charged with acetylene or a similar gas under high pressure, the valve 25 is turned to the "charge" position whereby the 60 passage 29 in the valve connects the pipe 19 with the inlet passage 23 of the receptacle 22. Since the pressure in the receptacle 22 is at atmosphere the valve 35 is open and gas from the tank 18 therefore passes into the 65 receptacle until the pressure therein has been

raised sufficiently to overcome the tension of the spring 37 and the diaphragm 36. This causes the valve 35 to be closed and the pressure gauge 26 to indicate the five pounds pressure or thereabouts that is in the the 70 receptacle. During this time the passage 30 in the valve 25 is not connected to the outlet passage 24 of the receptacle.

The valve is now turned to the "discharge" position shown in Fig. 1 whereby 75 the passage 29 is disconnected from the inlet 23 thereby cutting off the tank 18 from the receptacle 22 and the passage 30 connects the outlet passage 24 of the receptacle to the pipe 20 and thereby to the inlet conduit of 80 the engine.

At the same time that the valve 25 is turned to the "discharge" position the engine is turned over or cranked by hand or otherwise and a spark is formed in one of 85 the cylinders that is in position for firing. The charge of acetylene gas and air is thereby drawn into the cylinders and the explosions follow. The engine will run for some time on the charge of gas in the receptacle 90 22 and if it does not then pick up its charge of gasoline mixture from the carburetor 13 the receptacle 22 may be again quickly charged by turning the valve 25 first to the left and then to the right and the engine 95 will run for another period on the acetylene gas. This process may be repeated as often as is necessary to get the engine to pick up on its gasoline carburetor mixture with the assurance that the acetylene gas is being fed 100 to the intake manifolds at a low pressure only.

While I have herein described in some detail a specific embodiment of my invention, which I deem to be new and advantageous and may specifically claim, I do not desire it to be understood that my invention is limited to the exact details of the construction, as it will be apparent that changes may be made therein without departing from the 105 spirit or scope of my invention.

Having thus described my invention, what I claim and desire to secure by Letters Patent is:

1. In an internal combustion engine, the combination with the intake conduit thereof, of a source of gas supply under high pressure, a pipe connecting said conduit and source, a receptacle interposed in said pipe and having an inlet port and an outlet port, a diaphragm in said receptacle, a valve operated thereby to close the inlet port upon the obtaining of a predetermined pressure in said receptacle, a manually operable valve, controlling both said ports, said valve being adapted to close said inlet port ahead of said diaphragm actuated valve while said outlet port is open and vice versa.

2. In an internal combustion engine, the combination with the intake conduit, of a

charge measuring device comprising a receptacle having an inlet and an outlet, a valve for said inlet, a diaphragm controlled by the pressure within the receptacle and connected to close said valve at a predetermined pressure and a valve in series with said first-mentioned valve and having means to control said outlet.

3. In an internal combustion engine in combination with the intake manifold thereof, of a source of high pressure gas supply, a measuring receptacle having an inlet and an outlet, a regulating valve actuated by the pressure of said gas in said receptacle to control said inlet, pipes connecting said inlet to said source of gas and said outlet to said manifold, respectively, and a composite

valve interposed in said pipes and adapted to connect said receptacle to either or isolate it from both.

4. In an internal combustion engine, in combination with the intake manifold thereof, of a source of high pressure gas supply, a measuring receptacle having an inlet and an outlet, a pressure regulating valve actuated by the pressure of said gas in said receptacle to control said inlet, pipes connecting said inlet to said source of gas and said outlet to said manifold, respectively, and means to indicate at all times the pressure in said receptacle.

In testimony whereof I affix my signature.

LIONEL M. WOOLSON.
